UNITED STATES PATENT OFFICE.

JOSEPH MAYER, OF YONKERS, NEW YORK.

CORSET.

SPECIFICATION forming part of Letters Patent No. 328,130, dated October 13, 1885.

Application filed December 1, 1884. Serial No. 149,227. (No model.)

To all whom it may concern:

Be it known that I, JOSEPH MAYER, of Yonkers, in the county of Westchester and State of New York, have invented an Improvement in Corsets, of which the following is a specification.

Corsets have been made with eyelets at the back, near the edges of the half sections, and through these eyelets a lace has been threaded. Corsets have also been made with rows of eyelets in the sections for the reception of laces, by means of which the corset has been laced up to vary its shape. These eyelets, as far as they went, acted as ventilators to the corset.

My invention is made for lessening the labor of uniting the sections of the corset together, for increasing the strength of the corset, and at the same time for ventilating the entire corset.

In the drawings, Figure 1 is a representation of one-half of a corset, and Fig. 2 is a section in larger size, showing the manner in which the edges of the corset sections are united by the eyelets.

The sections composing the corset are cut out of the usual heavy woven fabric, and the edges of the sections that come outside are folded in. The sections are stitched together to form the bone-pockets, and the sections are prepared in the usual manner in all respects, except in regard to the uniting of one section to the other. The drawings illustrate the shape of sections that may be used; also, the clasp and steels at *a*, and the eyelets for the lacings at *b*. These parts may be of any desired character.

In the manufacture of corsets difficulty has heretofore arisen in uniting one section to the next in such a firm and reliable manner that there is no risk of such sections separating or 40 the stitching breaking apart under the strain to which the parts are often subjected.

My present invention relates to the corset in which the sections are united by eyelets to render the union of the sections more durable, 45 and at the same time to form openings that ventilate all parts of the corset.

In carrying out my invention the edge *i* of one section is introduced between the inwardly-folded edges *o o* of the next section, and the 50 thicknesses of the fabric are perforated, and eyelets *s* introduced and clinched in the usual manner, so as to firmly unite the sections together and render the corset very strong and durable.

Any ordinary eyeleting-machine may be employed for inserting these eyelets.

I claim as my invention—

A corset composed of sections of woven fabric with the usual stitching to form the bone-pockets, and the sections united by eyelets that pass through the edges of one section and the inwardly-turned edges of the next section for uniting and strengthening the seams and forming ventilating-openings, substantially as 60 set forth.

Signed by me this 26th day of November,
A. D. 1884.

J. MAYER.
